UNITED STATES PATENT OFFICE.

WINSLOW JONES, OF SEATTLE, WASHINGTON.

CUTTER HEAD.

Application filed January 24, 1927. Serial No. 163,190.

My invention relates to the art of cutterheads. More particularly my invention relates to a cutterhead having an improved means for holding the knives on the faces thereof.

A primary object of my invention is to provide a cutter head which will be characterized by the following features: closeness of clamping of the knife to its cutting edge; wide range of adjustability of the knife both in magnitude and direction, i. e., crosswise and lengthwise of the face of the cutter head; the non-spreading of the cutterhead under the severe strains to which it is subjected; non-interference of the clamping means with the material being operated upon; adaptation of the cutterhead to the use of thin and thick knives; by the elimination of vibration of the cutting edge continuously throughout its use, that is, initially as well as after being worn away by long use and grinding; by having the clamping means depressible at right angles to the cutter head face; and by having the knife function as a binder between the parts of the head on each side of the holding aperture in the face which prevents distortion of a cutterhead.

The above general objects of my invention, together with others inherent in the same, are obtained by the device illustrated in the following drawings, the same being preferred exemplary forms of embodiment of my invention throughout which drawings like reference numerals indicate like parts:

Figure 1 is a view in side elevation of a cutter head embodying my invention.

Fig. 2 is a view in perspective of a cutter head embodying my invention.

Fig. 3 is a view in end elevation of a cutter head embodying my invention.

Fig. 4 is a view of a knife embodying my invention.

Fig. 5 is a view of one form of clamping means.

Fig. 6 is a view in side elevation of a modified form of a clamping means embodying my invention in applied position with the knife.

Fig. 7 is a view in end elevation of said modified form shown in Fig. 6.

Fig. 8 is a view of another modified form in side elevation of clamping means embodying my invention in applied position with the knife.

Fig. 9 is a view in end elevation of the modified form shown in Fig. 8.

Fig. 10 is a view in side elevation of still another modified form of clamping means embodying my invention in applied position with the knife.

Fig. 11 is a view in end elevation of the modified form shown in Fig. 10.

Fig. 12 is a view in side elevation of a further modified form of clamping means embodying my invention in applied position with the knife.

Fig. 13 is a view in end elevation of the modified form shown in Fig. 12.

Fig. 14 is a view of a cutter head embodying an aperture of round form.

Fig. 15 is a view of a modified form, i. e., a pin form of clamping means to be disposed in said aperture.

Fig. 16 is a view on dotted line 16—16 of Fig. 14.

A cutter head 14 is provided with a plurality of faces 15. These faces provide bearings for the knives 16 each of which has the cutting edge 17. The face 15 is preferably provided with a milled surface 18 and likewise the knives 16 are preferably provided with a milled base 19 adapted to register with the milling of the face 15. In the face 15 an aperture 20 is provided, which in Figs. 1 to 13 inclusive is illustrated in the form of a slot longitudinally disposed of the cutter head.

In the longitudinally disposed slot a clamping means 21 is provided under the flanges 22 of which the lateral flanges 23 of each knife 16 may pass. In the periphery of the cutter head a clamping screw hole 24 is provided. In this hole a threaded set screw 25 may be inserted having a reduced bearing 26 which may be brought to bear upon the bevelled seat 27 of the clamping means 21.

In the modified form shown in Fig. 6 a T slot 28 may be provided in the knife 29 and the clamping member 30 may be provided with a corresponding T head 31 to fit in said T slot of the knife, the clamping means 30 having a bevelled seat 32.

In the modified form shown in Fig. 8 a groove 33 may be provided in the side of the knife 34 which may be engaged by the flanges 35 of the clamp means 36, the clamping means having a bevelled seat 37. In short, this form represents the opposite of the form shown in Fig. 6.

In modified form shown in Fig. 10 the knife 38 may be provided with a base having bevelled side walls 39, engageable by corre-

sponding bevelled walls 40 of the clamping means 41, which means has the bevelled seat 42.

In the modified form shown in Fig. 12 a 5 knife 43 may have the dovetailing walls 44 to engage corresponding bevelled walls 45 of the clamping means 46, which means has the bevelled seat 47.

In the modified form shown in Fig. 14 the 10 knife bearing face 48 is provided with an aperture 49 in the form of a round hole into which the modified form of clamping means 50 in the form of a pin may be inserted. This clamping means may have the T form 15 of head 51 to engage a corresponding T slot opening 52 of knife 53, the clamping means in the form of the pin having the bevelled seat 54 against which may be brought to bear 20 the set screw 55. The face 48 may or may not be provided with a milled surface.

The mode of operation of a device embodying my invention is as follows:—

The knife 16 is placed with its milled base upon the milled face 15 slipping the lateral 25 flanges 23 of the knife under the flanges 22 of the clamping means 21. Thereupon, the set screw 25 is inserted in the clamping screw hole 24 and is screwed down hard against the bevelled seat 27 which causes the knife 16 30 to be held firmly against the face 15. It will be noted that the longitudinally disposed aperture in the form of a slot is located in close proximity to the cutting edge 17 of the knife so that vibration in said cutting end 35 portion of the knife 16 is eliminated. In thus disposing the aperture longitudinally of the cutter head, it is manifest that the cutter head under each face is divided into two parts, namely, 56 and 57. The part 56 40 would be distorted by the severe strains to which it is subjected if special provision was not made therefor. Accordingly the knife 16 is caused to function as a binder between parts 56 and 57, i. e. the parts on each side of 45 the slot 20 are firmly held together in an obvious manner by the clamping of the knife member down upon the face, since the milling 18 of the face registers with the milling 19 of the knife.

50 In eliminating the vibration in the cutting edge, it is manifest that chattering is eliminated and a very smooth surface is provided in the material being operated upon, also holding the knife edge free of vibration results in maintaining the tool in a sharp condition much longer than ordinarily obtains and thus eliminates expense incident to frequent grinding of the knives. Also, it is manifest 55 that the knife 17 may be ground away in 60 sharpening and ready adjustment made by moving the knife forward on the face, and at all times the distance from the clamping means to the cutting edge is constant. This is in direct contrast with many knives of the prior art, which do not have this constant

distance between the clamping means and the knife edge, i. e., as the knife edge is ground away the distance ordinarily between the clamping means and the knife edge is reduced and a much restricted life of the knife obtains in the prior art device. It is manifest 70 that the knife 16 embodied in my invention will be characterized by a long period of usefulness as it may be ground practically for a distance of two-thirds or more of its length. 75

A wide range of adjustability is likewise manifestly present in my invention. The knife may be disposed near the front end of the cutterhead by pushing the same forward or back as desired and the knife may be disposed in a plane transversely of the cutterhead the desired extent by merely sliding the clamping means 21 longitudinally of the cutterhead. Also, it is manifest that the top of 80 the knife is entirely free of any clamping means which will interfere with the work or material being operated upon.

These advantages are obviously inherent 85 in my invention as a result of providing a clamping means which is depressible at right angles to the face in contrast to bolting the knife to the cutterhead, which does not provide for actuating the clamping means at right angles to the face and in a direction towards the axis of the cutterhead. It will be 90 noted that the slot 24 has the empty space 58 underneath the clamping means which may be of any desired depth to permit the approaching of the clamping means 21 to the bottom 95 of said slot.

Moreover, it is noted that the cutterhead is adapted to the use of thin or thick knives as the particular requirement may dictate.

In the modified form of clamping means shown in Figs. 6, 8, 10, 12 and 16 it is manifest 105 that the clamping means may be disposed entirely within the knife itself, and thus in no wise interfere with the work.

In the modified form shown in Fig. 16, the form of the aperture 49 is round and thereby 110 avoids weakening the cutter head and may be preferred for some classes of work to the slot arrangement.

Obviously changes may be made in the 115 forms, dimensions and arrangement of the parts of my invention, without departing from the principle thereof, the above setting forth only a preferred form of embodiment.

I claim—

1. A cutter head embodying a face; an aperture in said face located in close proximity to the forward edge of said face; a clamping means operatively disposed in said aperture having a bevelled seat; a knife; a clamping screw hole in said clamping head beneath the cutting edge of said knife; and a clamping screw operatively disposed in said screw hole to bear against said bevelled seat, whereby said knife may be held securely against said face and operate to hold the parts of said cut- 120
- 125
- 130

ter head on each side of said aperture together.

2. A cutter head embodying a face having interlocking means disposed therein; an aperture in said face located in close proximity to the forward edge of said face; a clamping means operatively disposed in said aperture having a bevelled seat; a knife having a mounting base provided with means which 10 interlock with the interlocking means on said cutter head; a clamping screw hole in said clamping head beneath the cutting edge of said knife; and a clamping screw operatively disposed in said screw hole to bear against 15 said bevelled seat, whereby said knife may be held securely against said face and operate to hold the parts of said cutter head on each side of said aperture together.

3. A cutter head embodying a milled face; 20 a slot disposed longitudinally of the cutter head, said slot being in close proximity to the forward edge of said face; a clamping means operatively disposed in said slot having a bevelled seat; a knife having a milled

mounting base; a clamping screw hole in said 25 clamping head beneath the cutting edge of said knife; and a clamping screw operatively disposed in said screw hole to bear against said bevelled seat whereby said knife may be held securely against said face.

4. A cutter head embodying a milled face; a slot disposed longitudinally of the cutter head, said slot being in close proximity to the forward edge of said face; a clamping means 30 operatively disposed in said slot having a bevelled seat disposed as respects said face; a knife having a milled mounting base; a clamping screw hole in said clamping head beneath the cutting edge of said knife, said hole being disposed at an angle to the radius 35 of said cutter head; and a clamping screw operatively disposed in said screw hole to bear against said bevelled seat whereby said knife may be held securely against said face.

In witness whereof I hereunto subscribe 40 my name this 13th day of January, A. D. 1927.

WINSLOW JONES.
